UNITED STATES PATENT OFFICE.

EDWARD G. THOMAS, OF BOSTON, MASSACHUSETTS.

DESIGN FOR A FILM-HOLDER.

SPECIFICATION forming part of Design No. 29,317, dated September 6, 1898.

Application filed August 9, 1898. Serial No. 688,214. Term of patent 7 years.

To all whom it may concern:

Be it known that I, EDWARD G. THOMAS, of Boston, in the county of Suffolk, State of Massachusetts, have invented and produced 5 a new and original Design for Film-Holders, of which the following is a specification, reference being had to the accompanying drawing, forming a part thereof.

The leading or material feature of the de- 10 sign consists in the unitary article made the subject of the illustration—that is to say, in the film-holder having the shape and config- 15 uration shown. Described specifically, it has the end bars A A', side bars B B', and over- lapping extensions C C' of the side bars,

which are separated from the side bars of the longitudinal recesses c c', and the handle or finger D, the design forming a frame sur- 20 rounding the opening E, which is substan- tially rectangular in shape.

Having described my invention, what I claim as new, and desire to secure by Letters Patent of the United States, is—

The design for a film-holder as herein shown and described.

EDWARD G. THOMAS.
